EDWARD B. HESS, OF NEW YORK, N. Y., ASSIGNOR TO ROYAL TYPEWRITER COMPANY, OF HOBOKEN, NEW JERSEY, A CORPORATION OF NEW JERSEY.

WRITING-MACHINE.

No. 858,343.

Specification of Letters Patent.

Patented June 25, 1907.

Original application filed September 1, 1906, Serial No. 332,940. Divided and this application filed April 11, 1907.
Serial No. 367,845.

To all whom it may concern:

Be it known that I, EDWARD B. HESS, a citizen of the United States of America, residing in the borough of Brooklyn, city and State of New York, have invented certain new and useful Improvements in Writing-Machines, of which the following is a specification.

This application, which is a division of my application No. 332,940, filed September 1, 1906, relates particularly to front strike writing machines and comprises means for protecting the key levers, type bars and bearings of the latter from dust and dirt of erasure, devices whereby the alinement, vertically and horizontally of the line of print, is maintained.

In the accompanying drawings, Figure 1 is a perspective view showing a complete front strike typewriting machine to which the improvements constituting the subject matter of this application are applied; Fig. 2, a detail view showing a type bar in a type bar guide at the printing point; Fig. 3, a perspective view of a type bar constructed in accordance with this invention; and Fig. 4, a longitudinal vertical central section.

In front of the platen *a*, contiguous to the printing point, is mounted an ordinary type-bar guide in the channel between the jaws *d* of which the type bars are guided to the printing point. Centrifugal action tends to move the heads of the type-bars away from their axes and, if there be slight lost motion, due to wear or for other reasons, the type head may, at the moment of printing, be thrown somewhat above the proper position, making the impressions more or less out of the line of print. Such defective operation of the machine may be overcome by providing on the respective type bars, a lateral guide stop that engages the under face of one of the jaws *d* of the guide and prevents tendency of the type bar head under centrifugal action from increasing its radius of movement.

A practical and efficient embodiment of this invention is depicted in the drawing and is as follows. On the type bars closely adjacent the type heads and on the inner sides of the angle of the bent bars, is a guide stop *c* which, when the part of the type bar between it and the type head enters the chan-

nel of the guide, may come against the under side of one of the jaws *d* of the guide and positively determines the position, vertically, of the type bar head with reference to the line of print should there be sufficient lost motion to otherwise permit the type head to move vertically and carry the type above its proper position. It is preferred that the face of the guide stop that may contact with the horn *d* be beveled as indicated at *c'*, its highest edge being at *c''*, so that as it passes under the type bar guide its high edge will contact therewith. This particular construction and shape is adopted in order to eliminate tendency of the type bar to stick in the guide. In practice, it is sufficient that such a guide stop be placed on one side only of each type bar. The guide stops *c* on one side of the center line of the machine all point to the right and on the other side all point to the left.

A segment *e* in which the type bars are pivoted has attached to it, or formed with it, a forwardly projecting curved flange *f* of the same radius as the curve in which the type bars are pivoted; and each type bar has, in its upper edge a recess *g* into which such flange enters as the type bar comes to the printing point. The flange overhangs all the slots in the segment in which the type bars are pivoted and swing, and the thickness of the segment at the upper walls of the type bar slots is such that it extends well to the rear and front of the type bar pivots affording protection from dirt of erasure falling either in front or in rear of the segment. The type bar pivots are substantially in line below the line of print so that if the pivots were unprotected the dirt and grit of erasure would fall directly upon them. This arrangement, of itself, is not claimed herein having been shown and claimed by me in an application, Serial No. 246,493, filed February 20, 1905 (a renewal of application No. 73,570, filed Aug. 28, 1901,) and is now before the Patent Office in a division of said application filed June 30, 1903, Ser. No. 163,691.

In the machine herein illustrated, the ribbon bobbins are located below the top of and inside the machine. The ribbon passes upwardly over idlers *h*, *h'*, located in apertures in side cover plates *h''*, *h'''* and, at the printing point, is a ribbon vibrator and guide *i* through

which the ribbon passes. The type bar guide is composed of two separated horns *d*, *d* projecting forwardly from upright angle plates *j* pivoted at *j'* near the upper horizontal edge of the type bar segment and made adjustable by means of slots and set screws *k*. Secured under the side cover plates *h* and supported in part by the ends of the segment are two dust sheds *m*, *n*, which extend inwardly, first, horizontally, and then incline upwardly to the type bar guide. Their front edges incline rearwardly and have the contour of a compound or reverse curve. Their inner ends, however, adjacent the type bar guide are in close proximity to the ribbon vibrator and extend somewhat forward of the guide and are sufficiently separated to permit free entrance of the type bars thereto. They are each provided with a downwardly turned vertical flange *o* at their inner ends that fits loosely in the angle of the type bar guide piece *j*; or the vertical edge of the flange *o* may lie back of the vertical piece *j*, and its horizontal edge 25 may rest upon the straight upper edge of type bar segment. At the angle formed by the downwardly extending flange *o* and at the extreme inner end of the upwardly inclined part, each dust shed is notched or cut away to fit the horn *d* of the type bar guide. The inner ends of the two dust shed sections and the contour of their front edges are such as to afford entirely free movement of the type bars to the printing point but otherwise 35 to give the greatest measure of protection to the type bar bearings and key levers above which they are disposed. With the arrangements described to project the type bars and by inclosing the front of the machine with a vertical frame plate *p* and the sides and rear with inclosure plates, the machine is as completely protected from intrusion of dust as it can possibly be. Access to the interior of the machine is afforded at desired places by 40 hinged panels *q* (one of which appears in Fig. 1) that may be placed in both side plates as well as elsewhere. For further protection against dust, the bottom of the machine may be closed by a plate. This closure of the 45 machine serves not only to exclude dust but also to render the machine less noisy than it would otherwise be and such noise as might occur in the operation of the machine may be further reduced by mounting it upon a pad of fibrous or elastic material.

Owing to the location of the ribbon vibrator and type bar guide and particularly because of the closeness of the ribbon vibrator to the printing point, it is not the custom of operators to make erasures directly at the printing point but to do it on either side thereof. While therefore some of the grit of erasure may fall down behind the flange *o* and be deflected by the segment from the 65 type bar pivots, the major part of it will fall

upon the dust guard sections *m*, *n*, and may be brushed away. The upper dust shed is, therefore, a more effective protection of the pivots than is the guard formed by the increased width of the segment adjacent the 70 type bar pivots. Ordinarily in machines heretofore constructed, the rear part of the segment has usually been so disposed as to protect the type bar pivots from grit falling in rear of the segment. The projection at 75 the front of the segment was designed as a protection against grit falling in front thereof and is, in a way, reasonably efficient, particularly in connection with the central type bars; but toward the ends of the segments 80 the flat type bars are turned with increasing angle as the end is approached so that their flat sides are not adequately protected by the forward projection of the segment and are liable to receive the dirt and grit of erasure at 85 either side of the printing point and a considerable portion of such dirt will work into the bearing of these bars. Experience has demonstrated that the upper dust shed *m*, *n* affords a highly efficient protection to the 90 pivots of the bars on either side of the central bars, and also to an important extent to the pivots of the central bars, because except for the sheds *m*, *n* the grit from erasures made to the right and left of the ribbon 95 vibrator would fall on the flange or shoulder *f* and work its way toward the center by reason of the inclination of the flange. If, therefore, such dirt of erasure as occurs on either side of the ribbon vibrator is intercepted by 100 the dust guard plates or sections *m*, *n*, the type bar pivots are protected to the greatest possible extent much more efficiently than they can be by the mere projection or flange *f* alone. It is feasible to have these upper 105 dust shed sections widely separated at the front so as to afford ready and convenient access, for cleaning, to the type bar heads as they lie closely side by side upon their back stop or rest. This arrangement of dust shed 110 at the type bar guide closely adjacent the printing point extending laterally and inclining outwardly at its front edge constitutes a material improvement in visible 115 writing machines of the general kind depicted in the drawing.

I claim:

1. In a front strike writing machine, a platen, a vertically arranged type bar segment, in which the type bars (that normally 120 lie in substantial parallel lines with their heads toward the front) are pivoted, constructed to overlie the pivots of the bars projecting in front and rear thereof to protect them from dirt of erasure, a dust shed composed of two sections arranged respectively with their inner ends closely adjacent the printing point and extending laterally therefrom with their front edges inclined outwardly whereby the type bar segment and 125 130

type bar bearings therein are protected from dirt of erasure occurring at either side of the printing point.

2. In a front strike machine, type bars normally lying toward the front of the machine in substantially parallel lines, a segment in which they are pivoted constructed to overhang the pivots at both the front and rear, and a dust shed arranged above the segment and composed of two sections whose inner ends are closely adjacent the printing point and which extend laterally and forwardly being widely separated at their front ends to permit access to the type bar heads.
- 15 3. In a front strike writing machine, a dust shed lying within the chord of the arc in which the type bars are pivoted and a second dust shed arranged above the chord of the arc and extending from closely adjacent the printing point laterally toward the sides of the machine.

4. In a front strike machine, a platen, a centrally disposed ribbon vibrator and a centrally disposed type bar guide in front of the vibrator, a dust shed composed of two sections having their narrow inner ends contiguous the guide and extending laterally with their front edges inclined outwardly, combined with a vertically disposed type bar segment having bearings for the type bars and constructed to overhang said bearings in front and rear.

5. A front strike writing machine comprising a platen, a centrally disposed ribbon vibrator and type bar guide, a dust shed composed of two sections whose narrow inner ends are contiguous to the guide and which extend laterally with their front edges inclined outwardly, combined with a type bar segment located below said dust guard, provided with bearings for the type bars and formed to project forwardly over said bearings.

6. In a front strike writing machine, a platen, a vertically disposed support located below the platen provided with bearings arranged in an arc for the type bars and a forward projection overhanging the bearings, type bars pivoted in said bearings and normally lying substantially parallel with their heads toward the front, and a dust shed arranged above the segment and extending on either side of the printing point.

7. In a front strike writing machine, a centrally disposed ribbon vibrator, a centrally

disposed type bar guide composed of two adjustable sections and a dust shed composed of two sections whose inner ends are closely adjacent the guide and which extend laterally therefrom.

8. In a front strike writing machine, a platen, a transversely arranged segment below the platen and substantially in line below the printing line thereon, type bars pivoted therein in an arc the segment being provided with means for protecting the type bar pivots from dirt of erasure, and a dust shed located above a chord passing through the pivots of the end type bars and composed of two sections whose inner ends are arranged closely adjacent the printing point and which extend laterally and forwardly with their front edges inclined outwardly.

9. A front strike writing machine comprising the combination of a segment located in a plane below the platen, type bars pivoted therein, side cover plates at each side of the assemblage of type-bars, ribbon guide rolls mounted in apertures in the cover plates, a ribbon guide and vibrator at the printing point through which the ribbon passes, a type bar guide at the printing point, and dust sheds extending from the side plates inwardly and upwardly to the horns of the type-bar guide and having rear vertical flanges o.

10. A front strike writing machine comprising the combination of a segment located in a plane below the platen, type-bars pivoted therein, side cover plates at each side of the assemblage of type-bars, ribbon guide rolls mounted in apertures in the cover plates, a ribbon guide and vibrator at the printing point through which the ribbon passes, a type bar guide at the printing point, dust sheds extending from the side plates inwardly and upwardly to the horns of the type bar guide and having rear vertical flanges o, a front plate closing the frame in front of the type-bar heads and plates closing the sides of the frame having panels or doors adapted to be opened to afford access to the interior of the frame.

In testimony whereof, I have hereunto subscribed my name.

EDWARD B. HESS.
